UNITED STATES PATENT OFFICE.

ALBERT CAMPBELL, OF ANACONDA, MONTANA.

OIL AND ACID FEEDER.

1,190,721.

Specification of Letters Patent. Patented July 11, 1916.

Application filed July 21, 1915. Serial No. 41,209.

To all whom it may concern:

Be it known that I, ALBERT CAMPBELL, a citizen of the United States, residing at Anaconda, in the county of Deerlodge and State of Montana, have invented certain new and useful Improvements in Oil and Acid Feeders, of which the following is a full, clear, and exact description, reference being had to the accompanying drawings, forming a part hereof.

My invention has relation to improvements in oil and acid feeders to flotation concentrators; and it consists in the novel features of construction more fully set forth in the specification and pointed out in the claim.

As well understood in the art, what is known as the flotation process of ore concentration contemplates the employment of a suitable frothing agent which is mixed with the ore-pulp, and which upon proper agitation and aeration with the pulp produces a froth which accumulates on the surface of the pulp, the ore particles clinging to said froth. Upon subsequent removal of the froth from the resulting gangue or tailings, the mineral values with which the froth is charged may be readily recovered.

The present invention is directed to apparatus which will feed such frothing agent (usually oil or acid, or oil and acid as well understood in this art) to the pulp in measured quantities, the object sought being to provide an apparatus in which this feed shall be constant and uniform irrespective of the quantity of said agent in the container or tank from which the same is fed to the ore stream.

A further object is to provide a feeder the speed of which may be readily adjusted and maintained under perfect control; one which is simple and light in construction, easy to operate; and one possessing further and other advantages better apparent from a detailed description of the invention in connection with the accompanying drawings in which—

Figure 1 represents a side elevation of the apparatus with the tank or container in section; Fig. 2 is an end elevation with parts in section; Fig. 3 is a top plan with supporting timbers omitted; Fig. 4 is a middle longitudinal sectional detail through the threaded end of the disk-shaft and through the friction wheel and adjusting wheel

therefor; Fig. 5 is an end elevation of the parts shown in Fig. 4, with parts broken away; Fig. 6 is an end view of the hub portion of the friction-wheel; Fig. 7 is a vertical sectional detail on a reduced scale on the line 7—7 of Fig. 8 showing only the bore and counterbore of the hub of the adjusting wheel; Fig. 8 is an enlargement of a part of the showing in Fig. 4; and Fig. 9 is a vertical middle longitudinal section taken through the inner sliding bearing of the disk-shaft.

Referring to the drawings, 1 represents a preferably steel tank or container with a lead lining 2 for holding the frothing agent (oil or acid, or both, depending on the character of agent employed) to be fed to the ore stream or pulp. Secured at one end of a bronze shaft 3 and adapted to rotate in the tank aforesaid, is a member or bronze disk 4, the direction of rotation thereof being indicated by the arrow in Fig. 1. Disposed on the front face of said disk adjacent the periphery thereof are a series of lead buckets or dippers 5 (of equal contents), the same being secured in place by bronze taper pins 6, the depth of submergence of the buckets in the liquid in the tank depending of course on the depth of the liquid which may be anywhere between a full tank and a minimum level represented by the dotted line x in Fig. 1. The face of the disk from which the buckets project is disposed in close proximity to the adjacent vertical wall of the upper terminal of a bent lead launder 7 of a shape substantially as shown, the bottom of the launder being suitably inclined so as to readily conduct away the liquid, the latter discharging into the lead pipe 8 on the outside of the tank, said pipe in turn conveying the liquid (or frothing agent) to a suitable point where it minglest with the ore stream or pulp designed for treatment in any approved form of flotation concentrating machine (not shown).

The launder 7 is bent laterally as shown (Fig. 3) the middle section or portion a being inclined to the terminal parallel portions b , c , on either side of it, this arrangement permitting the buckets or dippers to revolve around the upper section b , as well as the middle section a , and clear the lower section c , (farthest removed from the disk 4), as clearly apparent from the drawings. The launder is suitably supported at the

upper end by a bracket 9 leading from the tank, the lower end of the launder resting on the upper edge of the tank.

Disposed opposite the outer end of the disk-shaft 3, and at right angles thereto, is the main drive-shaft 10 to which rotation is imparted from any suitable motor (not shown) said shaft 10 carrying a spur pinion 11 which meshes with a spur gear 12 on a parallel counter-shaft 13, the latter terminating at its inner end in a friction disk 14 whose hub portion *m* is feathered to the shaft to allow for longitudinal adjustment of the disk thereon. The outer end of the hub *m* is closed by a cap or plate 15 in which is mounted an adjusting screw 16 bearing against the end of the shaft. By proper manipulation of the screw the hub *m* (and hence the disk 14) may be adjusted 20 to different positions longitudinally along the shaft, the purpose of the adjustment presently appearing.

Engaging the outer face of the disk 14 is a friction wheel 17 which is mounted on 25 the outer terminal screw-threaded portion *t* of the disk-shaft 3, the hub *n* of said wheel being provided with a feather key 18 which is free to slide in the featherway *d* formed in the threaded portion of the disk-shaft, 30 this arrangement permitting the wheel to rotate with the shaft and at the same time allowing for longitudinal adjustment thereof along the shaft. This longitudinal adjustment is effected by a hand wheel 19 whose hub portion *e* operates along the 35 screw-threaded section *t* and is loosely coupled to the hub *n* of the friction wheel. The connection between the respective hubs is effected by means of a ring 20 screwed to 40 the inner face of the hub *e*, the inner portion of the ring operating freely in an annular groove *u* behind the adjacent terminal flange or collar *w* of the hub *n*, it being obvious that the ring 20 must be made of two 45 or more sections to permit the insertion thereof into the groove *u* aforesaid. After the ring sections are properly placed they are secured in position by the screws *s* to which access is had through the spaces between the spokes of the wheel 17. It will 50 be seen from the foregoing that rotation of the adjusting wheel 19 (which operates as a nut along the threaded section *t*) will cause the same to be advanced along the disk-shaft 3, and being coupled to the friction-wheel 17, it will move the latter along said shaft (without however turning the wheel). These longitudinal adjustments 55 of the friction-wheel on its shaft 3 will cause its periphery to contact with the friction disk 14 at points of varying radial distance from the rotation axis of the disk, whereby the speed of rotation of the friction-wheel and of the disk shaft 3 may be 60 varied at will (Fig. 3). The speed of the

shaft 3 (and of the buckets 5) may be controlled by the operator while the machine is running on account of the slow rotation speed imparted to said shaft.

Once the friction-wheel 17 is properly 70 adjusted, it is necessary to lock the adjusting wheel 19 thereto to prevent accidental rotation of the wheel 19 along the shaft. To accomplish this, I provide the hub *e* of the adjusting wheel with a transverse passage or opening *p* terminating in a counterbore or enlargement *p'* whose outer terminal is covered by a plate 21. Operating loosely through the plate 21 is a stem 22 terminating in a head 22' which operates freely in 80 the passage *p*, the base of the head being provided with a collar 23 between which and the plate 21, and encircling the stem 22 is confined a coiled expansion spring 24 whose natural tendency is to force the head 85 22' inward. Leading from the passage *p* and opening through the shoulder *i* formed at the base of the counterbore *p'* is a slot *f* in which operates a pin 25 on the head 22'. As long as the pin 25 remains in the slot *f* 90 the spring 24 is free to force the head 22' against the flange or collar *w* of the hub *n* of the friction wheel 17. The collar *w* of the friction-wheel hub is provided with a series of marginal semi-circular (or equivalent) notches *y*; and when the pin 25 occupies the slot *f* it is apparent that if the adjusting wheel 19 be given a sufficient turn to bring the head 22' opposite one of the notches *y*, said head will automatically enter said notch under the driving action of the spring 24, and thus lock the adjusting wheel to the friction wheel. The two wheels thus locked will rotate as a unit about the axis of the shaft 3 during the operation of the machine for any given adjustment of the friction wheel. Should it be desired to change the position of the friction wheel (on the shaft 3) the operator 100 pulls on the stem 22 until he withdraws the head 22' out of its notch, and the pin 25 out of the slot *f*, when, by giving the stem a slight turn, the pin 25 may be brought opposite the shoulder *i* and allowed to rest thereon. This will prevent a return of the 110 head 22' against the collar *w*, leaving the adjusting wheel free to be turned on its shaft 3 and thus change the position of the friction wheel 17. Once the friction wheel is shifted to its new position, the adjusting wheel is again locked thereto by restoring the pin 25 to its slot *f*, when the spring 24 automatically effects a reengagement of the head 22' with one of the notches *y* designed to receive it. 115

The disk-shaft 3 is mounted in sliding bearings B, B', respectively, which are susceptible of slight adjustment to and from the friction-disk 14. This adjustment is effected by providing the bearings with elong- 120 125

gated slots s' through which pass the securing bolts 26. In the present embodiment of my invention, the bearing B is provided with a stem 27 traversing a bracket or abutment 28 between which and the bearing, and encircling the stem is interposed an expansion spring 29. The tension of the spring determines the pressure with which the friction wheel 17 shall bear against the face of the friction disk 14, this pressure being adjusted to suit conditions. In the present instance, the tension of the spring, and hence the friction between the members 14, 17, is regulated by the screw 16 which, according to the direction the same is turned, either drives the disk 14 toward the wheel 17 thereby compressing, and imposing greater tension on, the spring 29, or allows the disk 14 to recede from the wheel 17, the spring under the circumstances expanding. In this way the frictional engagement between the members 14, 17, may be carefully regulated to suit conditions.

The operation of the feeder may be described as follows: It was stated above that one of the objects sought is to secure a constant and uniform feed. Assuming rotation in proper direction to be imparted to the drive shaft 10 to cause the disk 4 to rotate as indicated by the arrow in Fig. 1, it will be seen that the buckets 5, in the event the tank 1 is full, will dip up a maximum quantity of liquid represented by a prism whose length corresponds to the width of the interior of the bucket, whose upper and lower faces correspond respectively to the surface of the liquid in the bucket and to the area of the bottom of the bucket, whose sides each correspond to the area of the shallow side wall g of the bucket (Fig. 1), and whose ends are substantially rectangles the areas of which are the product of the height of the wall g by the width of the bottom of the bucket. This would be the case with the bucket just emerging from a full tank or the bucket which has reached the position h in Fig. 1. When the bucket reaches the position h' some of the liquid will have been spilled or poured back into the tank; and when it reaches the position h'' the bucket begins to discharge into the launder or trough 7. By the time however that the bucket reaches the position h'' , the rectangular cross section of the prism of liquid 55 when at its maximum (at the point h) will be reduced to a prism whose cross-section is substantially a triangle, that is to say only about one-half of the liquid will be in the bucket at the point h'' as was in the bucket at the point h , the remainder having been discharged back into the tank between the points h and h'' . Of course as the level of the liquid in the tank lowers with the successive dipping out of the same into 60 the launder 7, the buckets will gradually

dip up less liquid, but in practising my invention the level of the liquid is never allowed to drop below a plane indicated by the dotted line x (Fig. 1) at which level the buckets will scoop or pick up a minimum 70 quantity, said quantity corresponding however substantially to the prism of liquid which is discharged into the launder from a bucket at the point h'' . It follows therefore that irrespective of the height of liquid 75 in the tank 1 between a full tank and the level indicated by x , the buckets will discharge a constant and uniform quantity of liquid into the launder, any excess or surplus which the bucket may contain over and 80 above said amount being spilled or returned into the tank before the bucket begins to discharge into the launder. This excess of course disappears when the level in the tank reaches a plane indicated by the line x , when 85 the buckets will pick up substantially the exact quantity to be discharged into the launder. This uniformity of discharge depends of course on the position which the launder 7 occupies relatively to the buckets, 90 that position being such as to allow the buckets to spill back into the tank the excess above a quantity represented by the minimum scooped up by a bucket or that which a bucket can pick up at the lowest 95 level (x). By thus delivering uniform and constant quantities of frothing agent to the launder 7, a uniform feed of the agent may be delivered to the ore pulp which is to receive it, and uniform results may be expected in the flotation machine or concentrator. The speed of the shaft 3 and of the buckets 5 may be changed at any time by shifting the friction wheel 17 along the friction disk 14 as above described (Fig. 3). 100

I may of course depart from the details here shown without in any wise affecting the nature or spirit of the invention. Features shown but not alluded to are well known in the art and require no description in the 110 present connection.

The apparatus of course need not be restricted to the feeding of oil or acid or a frothing agent to flotation concentrators, but may be employed in other arts and industries. Neither is the same to be limited to the feeding of liquids, it being applicable to solids or any fluent material whether liquid or solid.

Having described my invention what I 120 claim is:

In a liquid feeder of the character described, a suitable tank or container, a rotatable member operating in the tank and partially submerged in the liquid in the tank, a 125 series of buckets of equal contents mounted on the member and dipping into the liquid in the tank, an inclined launder positioned adjacent the rotatable member and the buckets comprising terminal sections con- 130

nected by an intermediate section inclined to the terminal sections and to the plane of rotation of the buckets and of the rotatable member, the buckets being secured to 5 the rotatable member to permit their revolution around the upper and the medial inclined section of the launder, the lower section being farthest removed from the rotatable member and out of range of the plane 10 of rotation of the buckets, the upper section of the launder being positioned relatively to the buckets to receive the minimum quan-

15
tity of liquid dipped up by the buckets irrespective of the level of the liquid in the container, and to permit a return into the tank of any excess of liquid over that discharged into the launder.

In testimony whereof I affix my signature in presence of two witnesses.

ALBERT CAMPBELL.
